UNITED STATES PATENT OFFICE.

VERONIKA KASMAUSKI, OF CHICAGO, ILLINOIS.

BELT.

1,319,650.

Specification of Letters Patent.

Patented Oct. 21, 1919.

Application filed May 6, 1919. Serial No. 295,103.

To all whom it may concern:

Be it known that I, VERONIKA KASMAUSKI, a citizen of the Republic of Lithuania, residing at Chicago, in the county of Cook and 5 State of Illinois, have invented a certain new and useful Improvement in Belts, of which the following is a full, clear, concise, and exact description, reference being had to the accompanying drawings, forming a 10 part of this specification.

My invention relates to belts and has to do more particularly with belts adapted for use as abdominal supporters. In stout people, the weight of the internal organs and 15 abdomen is thrown principally upon the muscles of the lower abdomen, which are continually under a strain and not being reinforced by any bony structure at times permit displacement of the internal organs. 20 One of the principal objects of my invention is to provide an improved and simplified belt of this character particularly effective in supporting the lower abdomen.

In the accompanying drawing, I have 25 illustrated the preferred form of my invention, in which—

Figure 1 shows the belt in use; and Fig. 2 is a view of the belt spread out flat.

Referring now more particularly to the 30 preferred form of my invention as shown in Fig. 2, it comprises a body member 5, preferably of a webbed elastic material, having suitable ends 6 and 7 perforated at 8, 9, and provided with eyelets so that the belt may 35 be laced as indicated in Fig. 1. These end pieces 6, 7 are preferably made of leather or other suitable substance capable of standing the strain incident to the lacing up of the belt.

40 In order to give the proper support, I provide suitable strengthening ribs or stays disposed along the belt, these ribs being made of steel or whale-bone strips of the usual construction and preferably covered with leather. At the back of the belt I attach a 45 suitable number of ribs 11, the number depending upon the size of the belt, spacing them about two inches apart. Adjacent these back supports 11, I provide intermediate ribs 12, 13. At the hip portions crossed ribs 14, 15 are provided and so positioned as to come immediately above the hips. These 50 crossed stays, I find, are particularly effective in holding the belt in place at the hips stiffening the belt. At the front of the belt

at each end, I provide front intermediate ribs 16, 17, which are positioned between the hip ribs 14, 15 and the lacing members. I also preferably attach ribs 18, 19 adjacent to ends of the belt but beneath the leathers 6, 7 60 so as to provide a suitable support at the meeting or front portion of the belt.

These ribs are suitably attached to the cloth strip 5 by sewing along the edges thereof. The edges 20, 21 of the belt are 65 preferably turned over or hemmed so as to protect the ends of the ribs or stays.

By means of the ribbed reinforcement the belt may be drawn up quite tight without having it fold over on itself as occurs in 70 some of the belts. This helps keep the belt in proper place and also assists in holding the covered part of the body firm.

In applying the device, as shown in Fig. 1, I preferably place a fine woolen band 22 75 between the belt and the body, this band absorbing the moisture given off by the body and not only keeping the body warm but also protecting the flesh against rubbing by the belt. This woolen band may be attached to the belt if desired.

What I claim as new and desire to secure by Letters Patent is:

1. An abdominal supporter comprising a belt, means for lacing the ends of the belt, 85 and crossed stays positioned at the hip portions of the belt.

2. An abdominal supporter comprising a belt, a wool lining therefor, means for lacing the ends of the belt, front and back vertical 90 stays, and crossed stays positioned at the hip portions of the belt.

3. An abdominal supporter comprising a webbed elastic belt, means for lacing the ends of the belt in front extending across the 95 full width of the belt, front and back stays, crossed stays at the hip portions, and front and back intermediate stays of less length than the width of the belt.

4. An abdominal supporter comprising a 100 wool lined belt in which the wool is placed next the body of the wearer, stayed leather lacing pieces at the ends of the belt, crossed stays on those portions of the belt adapted to fit the hips of the wearer, and intermediate stays adjacent said crossed stays, of less 105 length than the width of the belt.

In witness whereof I hereunto subscribe my name this 29th day of April A. D., 1919.

VERONIKA KASMAUSKI.
